AUTOMATIC WINCH CONTROL

Kurt Mahnke, Wilkinsburg, Pa., assignor to Westinghouse Electric Corporation, East Pittsburgh, Pa., a corporation of Pennsylvania

Application February 10, 1944, Serial No. 521,817

2 Claims. (Cl. 254—173)

My invention relates to electric winch control systems, such as for towing winches and cargo winches. It is known to provide such systems with a master controller for manual control of the electric winch motor and also with automatic control means for controlling the motor in dependence upon the tension or length, or both, of the winch cable.

It is an object of my invention to provide a winch control system of the just mentioned type, which affords an improved maneuverability by permitting the operator to change more readily than in known systems from automatic to manual control and vice versa, for instance, for temporarily modifying, accelerating, reversing or otherwise altering an automatic towing performance.

Another object of my invention is to provide a winch control system of the type referred to with an improved master control unit in which a single master controller and a single handle, when placed in one position, serves to set the system for automatic control and, when placed in other control positions, serves also to govern the manually controlled winch operation.

Other objects and advantages of my invention will be apparent from the following description of the winch control system diagrammatically shown in the drawing as an example of the invention.

According to the drawing, the winch motor WM has its armature A connected with a shaft 1 which drives a reduction gear unit 2 whose output shaft 3 is in driving connection with the winch drum 4 for accommodating the rope or cable 5 to be paid out or reclaimed by the winch drive. The winch drum 4 is provided with an orbit gear meshing with planet gears 6 which, in turn, are in meshing engagement with a sun gear 7. The sun gear is rotatable relative to the drum 4 about an axis coinciding with that of the drum shaft and is firmly connected with a spider 8. The shafts about which the planet gears 6 rotate are mounted on the legs of this spider. The spider is biased by a spring 9 and provided with an electric contact 10 which cooperates with two stationary contacts 11 and 12. The spring 9 tends to hold the spider 8 in a position where the appertaining contact 10 is in engagement with the stationary contact 11. When the pull of cable 5 increases so that the corresponding drum torque exceeds the driving torque of the winch motor WM to such an extent as to overcome the force of spring 9, the contact 10 is separated from contact 11 and engages the station-

ary contact 12. This has the effect of controlling the automatic control devices of the systems so as to cause the motor WM to change its torque in the direction required for reducing the cable pull with the result of restoring the desired torque and pull conditions as will be apparent from the following description of the operation of the system.

5 A friction brake BR is provided in order to retard or stop the winch drum 4. This brake is normally biased by a spring towards its operative position and contains a magnet coil which, when energized, releases the brake.

10 The reduction gear unit 2 is provided with two limit switch devices. One of these devices has a travelling member 13 which reciprocates to and fro in accordance with the length of cable paid out by the winch drum. This travelling member is so adjusted that it engages and opens a contact 14 only when the safe maximum length of cable has been paid out, and it engages and opens another contact 15 when cable is heaved in beyond its safe minimum length. The opening of either contact 14 or 15 causes the control system 15 to deenergize the winch motor WM and to apply the brake in order to prevent damage to the winch machinery. This control effect of the extreme pay-out limit mechanism will also be understood in detail from the description of the operation of 20 the system given hereinafter. A normally open 25 switch S is provided for resetting the winch after an operation of the limit contact 14 or 15.

30 The second travelling member, when in its operative position engages a switch contact 17 so that the switch 17 remains open for small departures of the member 16 from its center position in either direction and is closed when this departure exceeds a given limit value. The member 16 is adjustable so that it can be set into its 35 center position for any desired length of cable paid out by the winch drum 4. As will be explained in a later place, the closure of switch contact 17 has the effect of controlling the winch motor automatically so as to pay out or reclaim 40 an amount of cable sufficient to restore the original position of member 16. As a result, this limit mechanism maintains the paid-out cable length automatically at an adjusted value or between 45 relatively narrow limits. For instance, if during 50 a towing operation, in heavy sea, the pull of the towing cable becomes so great as to force the drum 4 to pay-out an excessive length of cable, the limit switch 17 is actuated and causes the winch motor to reclaim enough cable for restoring 55 the original cable length without imposing

undue stress on the cable or the winch machinery.

The winch motor WM has a series field winding SF and a shunt field winding PF and is under control by two selectively operating line contactors IP and IR serving to connect the motor to the supply mains X and Y for operation in the pay out and reclaiming direction, respectively. The pay out contactor IP has two line contacts 31 and 32 for performing the just mentioned switching operation and is also provided with an interlock contact 33, which prevents the reclaim contactor IR from being energized as long as the motor is connected for pay out operation. Other contacts denoted by 34, 35 and 36 serve to tie up the pay out contactor IP with other relays of the systems. Similarly, the reclaim contactor IR has two line contacts 21 and 22, contact 23 for interlocking the contactor IP when the motor is energized for reclaiming operation, and three additional contacts 24, 25 and 26 associated with other control devices of the system.

A dynamic braking resistor RI is arranged in parallel to the motor armature A, and controlled by the contact 41 of a relay DB, which has a second contact 42 for releasing the above mentioned friction brake BR. When relay DB is deenergized, the dynamic braking resistor RI is connected across the armature and the coil of the friction brake is deenergized so that this brake is also in operation. Conversely, the energization of relay DB renders the dynamic braking resistor RI ineffective and releases the friction brake BR.

The motor WM is further connected with a group of starting resistors R2, R3, R4 and R5, which are under control by respective relays 1A, 2A, 3A and 4A. Each of these relays has a main contact 51, 61, 71 or 81, and an interlock contact 52, 62 and 72, respectively, with the exception of relay 4A which has no such interlock. Due to the operation of these interlock contacts, each subsequent starting relay can be operated only after the preceding relay has connected its appertaining starting resistor to the motor.

A group of timing relays denoted by 1T, 2T, 3T and 4T serve to provide a given minimum period between the subsequent operation of the starting relays and are also associated with the automatic control relays described hereinafter. Each timing relay has an operating coil 91, 101, 111 or 121 and a group of contacts 92, 93, 94 and 102, 103, 104, and 112, 113, 114, and 122, 123, 124, respectively.

The contacts 10 and 12 are connected with the control coil 140 of a relay PR with three contacts 141, 142 and 143 serving to control the motor operation in response to the occurrence of excessive cable pull. Another relay RR has its coil 130 connected with the limit switch 17 and is provided with contacts, numbered 131 through 139, for controlling the motor in dependence upon the departure of the cable length from the adjusted value, as previously mentioned. The system is further provided with a low voltage relay LV, with a control coil 150 and three contacts 151, 152 and 153.

A single control unit CU is provided for governing the operation of the system selectively either by hand or automatically. The control unit CU contains a selector switch SS and a master controller MC. The selector switch SS has an "off" position, a "hand" position, and an "auto" position. In the "off" position, the master controller and the feed connections of the control relays are disconnected and, hence, inoperative. When placing the selector switch SS

on "hand" position, the automatic control devices of the system remain disconnected while the master controller MC becomes operative so that the system is under control by the master controller MC exclusively. When placing the selector switch SS on "auto," the automatic control devices are prepared for operation but their energizing connections extend through the master controller MC so that the automatic devices are only operative as long as the master controller is in its "off" position.

The master controller has a series of contact positions for pay out operation and for reclaiming operation. Its contact segments, numbered 171 through 176, engage corresponding contact fingers in selected contact positions of the master controller. Two of these segments, namely those denoted by 171 and 173 are disposed between the selector switch SS and the automatic control devices for the purpose already mentioned.

The above described control system operates in the following manner:

When the supply mains X and Y are energized by closing a main switch (not illustrated), the shunt field PF of the winch motor WM is immediately supplied with excitation. As long as the selector switch SS of the control unit CU is in its "off" position, the low voltage relay LV remains deenergized.

Moving the selector SS into "hand" or "auto" position causes a temporary closure of its contacts 163 and 164, thereby energizing the low voltage relay LV from X through circuit 163, 164, 171, 14, 15, 150, Y. Relay LV closes contacts 151, 152, and 153 and seals itself in through contact 151. If the relay LV is tripped, for instance by voltage failure, the selector switch SS must be returned to the "off" position before the operation can be resumed, and the master controller MC must also be in the "off" position, so that the relay circuit is closed at 171 for resetting the relay LV.

Manual control

With SS placed in the "hand" position, the winch is under control by the motor controller MC and operates as follows:

In the "off" position of MC, relay LV is sealed in as described above. The relays 1T, 2T, 3T, and 4T are energized. The main coil 90 of 1T is excited through X, 161, 171, 24, 34, 90, Y so that contacts 92 and 93 are closed while contact 94 is opened. Coil 100 of relay 2T is energized through Y, 100, 82, 152, 161, 163, X so that contacts 102 and 103 are closed while contact 104 is opened. Coil 110 of relay 3T comes in through Y, 110, 102, 152, 161, 163, X and closes contacts 112 and 113 while opening contact 114. Coil 120 of relay 4T is energized through Y, 120, 112, 152, 161, 163, X and closes contacts 122 and 123 while opening contact 124. The closure of contact 122 energizes the interconnected neutralizing coils 91, 101, 111, and 121 of the timing relays.

Upon turning MC to first point "payout," the dynamic braking relay DB becomes energized through Y, 40, 174, 153, 123, 113, 103, 93, 152, 161, 163, X and opens the circuit of resistor RI at contact 41. Simultaneously, the line contactor IP is energized through Y, 30, 23, 175, 174, 153, 123, 113, 103, 93, 152, 161, 163, X and connects the winch motor WM to the line at 31 and 32 through circuit X, SF, 31, A, R5, 32, Y. This connection includes the resistor R5. As a result, the motor is started in the payout direction. Both field windings SF and PF are now in operation.

The interlock contact 42 of relay DB energizes the coil of brake BR, thereby releasing the brake. Contact 34 of contactor 1P opens the circuit of coil 90 so that the timing relay 1T drops out after the elapse of its timing period.

On second point "payout" of MC, the coil 50 of contactor 1A is energized through Y, 50, 94, 175, 174, 153, 36, 151, 161, 163, X. Relay 1A closes contact 51 and thus connects resistor R2 in parallel to R5, thereby reducing the total resistance of the armature circuit. At the same time, coil 100 of timing relay 2T is deenergized by opening its circuit at 172 so that 2T falls off upon elapse of its timing period, thereby permitting the relay 2A to be energized on the next payout point of MC.

On third point "payout" of MC, relay 2A comes in through Y, 60, 52, 104, 175, 174, 153, 36, 151, 161, 163, X and closes contact 61, thereby connecting resistor R3 in parallel to R5 and R2. At the same time, the circuit of coil 110 is interrupted at 172 so that relay 3T drops out upon elapse of its timing period, thereby preparing relay 3A for operation.

On fourth point "payout" of MC, relay 3A is energized through Y, 70, 62, 114, 175, 174, 153, 36, 151, 161, 163, X and, at 71, connects resistor R4 in parallel to R5, R2, and R3. The circuit of coil 120 is opened at 172 so that relay 4T drops out upon elapse of its timing period thereby preparing relay 4A for subsequent operation.

On fifth point "payout" of MC, relay 4A is energized through Y, 80, 72, 124, 175, 174, 153, 36, 151, 161, 163, X and shorts resistors R2, R3, R4, and R5 at 81.

In review, the starting resistance in the motor circuit is successively lowered and eventually shorted out when the motor controller is passed from its "Off" position through its fifth point "payout."

If the master controller is thrown suddenly from "Off" to fifth point "payout," line contactor 1P will close immediately and relay DB will disconnect the braking resistor R1 and release the brake BR. After elapse of its timing period, relay 1T drops out and energizes relay 1A while deenergizing timing relay 2T. The latter, after elapse of its timing period, will energize relay 2A while deenergizing timing relay 3T and so forth until finally the relay 4A short circuits the starting resistors. Thus the minimum time of an operating sequence is determined by the adjustment of the timing relays, and the system is in fact under automatic control by these timing relays when the master controller is actuated at high speed.

When placing the master controller from its "Off" position on first point "reclaim," relay DB is energized through Y, 40, 174, 153, 123, 113, 103, 93, 152, 151, 161, 163, X and disconnects resistor R1 at contact 71. At the same time, the line contactor 1R is energized through Y, 20, 33, 176, 174, 153, 123, 113, 103, 93, 152, 161, 163, X and connects the winch motor WM to the line at 21 and 22 through circuit X, SF, 21, R5, A, 22, Y. As a result, the motor is started in the reclaiming direction, the brake BR being released by the closure of contacts 42 and 25. Contact 24 of relay 1R disconnects coil 90 of timing relay 1T so that the latter drops out after elapse of its timing period, thereby preparing relay 1A for operation.

On second point "reclaim," coil 50 of relay 1A comes in through Y, 50, 94, 176, 174, 153, 26, 151, 161, 163, X and connects resistor R2

in parallel to resistor R5 by closing contact 51.

These and all subsequent points "reclaim" of the master controller correspond to a control operation similar to the respective "payout" point except that the running direction of the winch motor is reversed. The minimum periods of the sequential starting steps are again determined by the time adjustment of the timing relays as described in the foregoing.

Automatic control

When the selector switch SS is placed into "Auto" position and the master controller left in its "Off" position, the winch drive is automatically controlled by the operation of the payout control switch 17, and the tensiometric contacts. In this position of switch SS, relay LV is energized and remains sealed in, and the timing relays 1T, 2T, 3T and 4T are also energized as described previously.

As long as the paid-out cable length remains within the extreme operating limits, as is normally the case, the travelling unit 16 remains somewhere between the limit switches 14 and 15 so that these two switches stay closed. Upon paying out a desired cable length, by means of the above-described manual control operation, the adjustable member 16 is set so as to engage switch 17. Hence, switch 17 remains open as long as the paid-out cable remains between relatively narrow operating limits as set by nut 16. Contact 10 of the tension-responsive device engages the contact 11 as long as the cable pull or tension remains below a given safe limit. If the tension increases beyond this limit, contact 10 engages the contact 12. This has the effect of energizing the pay-out relay PR by closing the circuit Y, 140, 12, 10, 173, 162, 152, 161, 163, X. Relay PR closes its contact 141 which bypasses the interlock contacts 24 and 34 of contactors 1R and 1P, respectively,

thereby maintaining an energizing circuit for coil 90 of timing relay 1T. Consequently, the timing relays 1T, 2T, 3T, and 4T remain excited and prevent the contactors 1A, 2A, 3A and 4A from closing their respective contacts. The closure of contact 142 in relay PR energizes the brake relay DB through circuit Y, 40, 142, 153, 123, 113, 103, 93, 152, 161, 163, X so that the dynamic braking resistor R1 is disconnected, at 41, from the armature A. Contact 143 of relay PR energizes the line contactor 1P through circuit Y, 30, 28, 143, 152, while the brake BR is released due to the closure of contacts 42 and 55 of relays DB and 1P, respectively. As a result, the motor WM will run in the pay-out direction, thereby reducing the cable tension. The speed torque characteristic of the motor, when so operating, corresponds to that of the first point "pay-out" of the master controller. Since, normally, the paid-out cable length remains within the extreme limit determined by limit switch 13, a condition will be reached where the cable tension has dropped sufficiently for disengaging the tension responsive contacts 11 and 12 so that the pay-out relay PR is deenergized, the motor stopped, and the brake set for operation. In the meantime, nut 16 has left its original position so that contact 17 is closed. Hence, when the cable tension drops to a point where the tensiometer contact 10 engages the contact 11 the reclaim relay RR is energized through circuit Y, 130, 17, 11, 10, 173, 162, 152, 161, 163, X. As a result, the line contactor 1R is excited via Y, 20, 33, 135, 153, 123, 113, 103, 93, 152, 161, 163, X and closes its contacts 21 and 22, thereby causing the winch

motor to run in the reclaim direction. At the same time, relay DB comes in over Y, 40, 134, 153, 123 and disconnects R1 from the armature A while releasing the brake BR. The motor accelerates until member 16 reaches its original position and opens contact 17 thus stopping the motor and setting the brake.

Combined automatic and manual control

It is an essential feature of my invention that the control means described in the foregoing are so interlinked that when the system is set for automatic operation, or during the actual performance of an automatic operation, the control can be taken over by the master controller merely by moving it out of its "Off" position. This is achieved by the fact that the connections between the automatically operating control elements and the relays controlled thereby extend through contact segments of the master controller which are so designed and located that the automatic control circuits can be completed only when the master controller is in the "off" position. That is the circuits necessary for the automatic operation are interrupted when the master controller leaves the "off" position, while the manually controllable portion of the system remains operatively connected to the master controller even if the system is set for automatic operation. Thus, the connection from the tensiometer contact 10 to the main X extends through the segment 173 of the master controller, this segment being so arranged that the circuit of pay-out relay PR or reclaim relay RR can be completed only if and as long as the master controller is in the "off" position.

As a result, the operator can at any time intervene into an automatic operation in order to perform a maneuver required by a momentary exigency, or he can modify or temporarily alter the operation of the towing winch system and then resume the automatic control merely by actuating the single handle or other manual of the master controller accordingly. For instance, if during an automatic reclaiming operation as described above, some amount of cable is to be paid out temporarily, the operator need merely turn the master controller in the "pay-out" direction. This causes the reclaim relay RR to be tripped, by disconnection of its coil 130 at segment 173, and the motor will reverse its direction and gradually accelerate corresponding to the selected controller point. To mention another example, if an automatic paying out is to be speeded up, the operator may turn the master controller temporarily on second to fifth point "pay-out." In any such case, the automatic operation is re-

sumed as soon as the master controller is returned to its "off" position.

It will be obvious to those skilled in the art, that a system according to my invention can be modified in many respects, especially as to details of the appertaining control devices, without departing from the essential features, objects and advantages of the invention. I, therefore, wish this specification to be understood as illustrative and not in a limiting sense.

I claim as my invention:

1. An electric winch control system comprising, in combination, a winch drum; a reversible motor in driving connection with said drum; automatic means for controlling said motor in response to given conditions of winch operation; a master controller for controlling said motor manually; current supply means; a manual selector switch disposed between said supply means on the one hand and said automatic means and controller on the other hand and having three positions for disconnecting said supply means from both said automatic control means and said master controller, connecting said supply means with said master controller alone, and connecting said supply means with both said automatic means and said master controller, respectively; said switch and said automatic control means being electrically connected with said master controller so that the connection of said automatic control means with said supply means through said switch is completed only when said master controller is in a position wherein the manual control is inoperative, and interrupted when said master controller is in any of its positions wherein the manual control is operative.
2. An electric winch control system comprising, in combination, a winch drum, a reversible motor in driving connection with said drum, automatic means for controlling said motor in response to given conditions of winch operation, a master controller for controlling said motor manually, current supply means, a manual switch for selectively connecting said supply means to said automatic control means and said master controller, said master controller having a plurality of operating positions in which the manual control is operative and an off position in which the manual control is inoperative and comprising contact means which are closed only in said off position, said contact means being electrically interconnected between said switch and said automatic control means so that the latter can be rendered operative by said switch only when said master controller is in said off position.

KURT MAHNKE.
